STEPLADDER

George E. Loucks, Belle River, Ontario, Canada

Application June 15, 1951, Serial No. 231,821

2 Claims. (Cl. 228—31)

1

This invention relates to step ladders and has particular reference to a ladder which will not tip over when in use.

An object of the invention is to generally improve step ladders and to provide a ladder which is inherently stable, simple in construction, economical to manufacture, and efficient in use, and one which may be folded into a comparatively small space for storing and transporting the same.

Another object of the invention is to provide a ladder with a tripod-like structure for bracing the same.

The foregoing and other objects and advantages of the invention will become more apparent as the description proceeds, reference being made from time to time to the accompanying drawings, in which:

Fig. 1 is a rear elevational view of a ladder embodying the invention.

Fig. 2 is a vertical section, taken substantially on the line 2—2 of Fig. 1.

Fig. 3 is a section, taken substantially on the line 3—3 of Fig. 2.

Fig. 4 is a side elevational view of the device in folded position.

Referring now more particularly to the drawings, it will be understood that in the embodiment herein disclosed, the reference characters 7 and 8 indicate the side rails of a conventional ladder, having steps 9, 10, and 11, which may be secured to the side rails 7 and 8 in any conventional manner. The side rails 7 and 8 are provided with a top plate 12, which overhangs the side rails 7 and 8 at the rear as at 13, to provide a support for the legs 14, 15, and 16, which are pivotally secured at their upper ends in the clevises 17, 18, and 19. The clevises 17 and 19 are also arranged to rotate about the pivots 17A and 19A.

Intermediate the ends of the side rails 7 and 8, and pivotally secured thereto, as at 20 and 21, is a U shaped member 22. To the underside of the web portion of the U shaped member 22, I pivotally secure, as at 23 and 24, a pair of clevises 25 and 26, to which are respectively pivoted the arms 27 and 28, which are in turn pivoted at their other ends, as at 27A and 28A, to the legs 14 and 16. A third clevis 29 is secured to the underside of the web portion of the member 22 and has pivoted to it the arm 30, the other end of the arm 30 is pivoted as at 31 to the leg 15.

The upward rocking of the member 22 on its pivots 20 and 21, causes the legs 14, 15, and 16 to be drawn inwardly by means of the arms 27, 28, and 30. In order to rotate the legs 14 and 16

5 on the pivots 17A and 19A (Fig. 1) when the legs 14 and 16 are being moved outwardly at the bottom, under the influence of the U shaped member 22 and connecting arms 27 and 28, I provide the springs 32 and 33 which are connected to chains 34 and 35 which extend between the legs 14 and 16 and the side rails 7 and 8. I also provide chains 36 and 37 between the leg 15 and the legs 14 and 16. The chains 36 and 37 serve to limit the movement of the legs 14 and 16 under the influence of the springs 32 and 33, and also serve to stabilize the legs 14, 15, and 16 when the device is in use.

10 In Fig. 4, I illustrate the position of the component parts when the device is folded for storage or transportation.

15 In order to set the ladder up for use, the side rails 7 and 8 are first rested upon the ground and the operator extends his hand between the rails 7 and 8 and grasps the U shaped member 22, rocking it downwardly. The downward movement of the member 22 causes the outward movement of the arms 27, 28, and 30, which in turn force the outward movement of the lower ends of the legs 14, 15, and 16. During the outward travel of the lower ends of the legs 14, 15, and 16, the springs 32 and 33 will also cause the legs 14 and 16 to rotate about their longitudinal axes on the pivots 17A and 19A, which rotation will be limited by the chains 36 and 37.

20 In folding the device, it is necessary to manually rotate the legs 14 and 16 in the opposite direction against the action of the springs 32 and 33. This manual rotation of the legs 14 and 16 becomes increasingly easy as the lower ends of the legs 14, 15 and 16 are moved inwardly under the influence of the arms 27, 28, and 30, and the upward movement of the member 22.

25 From the foregoing, it will be seen that I have provided a step ladder with a novel means of bracing the ladder against any tendency for the ladder to tip over when in use.

Having described my invention, what I claim and desire to secure by Letters Patent is:

30 1. In a device of the character described, including a pair of side rails and a plurality of steps secured thereto, the combination of a top plate, three clevises secured to the underside of said plate, two of said clevises being rotatable with respect to said plate, a leg pivoted to each of said clevises, a U shaped member pivoted to said side rails, three clevises pivoted to said U shaped member, two of said last named clevises being rotatable with respect to said U shaped member, arms pivoted to said last named clevises and to

points intermediate the ends of said legs, spring means extending between said side rails and the two of said legs secured to said rotatable clevises, and chains extending between said last mentioned legs and the third leg, whereby to limit the outward movement of said two legs.

2. The combination with a ladder, of a top plate having an overhanging portion, at least three clevises secured to the overhanging portion of said plate, two of said clevises being rotatable, a leg pivoted to each of said clevises, a U shaped member pivoted to the side rails of said ladder, at least three clevises secured to said U shaped member, two of said last named clevises being rotatable with respect to said U shaped member, an arm pivoted to each of said last named clevises and to one of said legs, and flexible

5

means extending between said legs and between the legs and said side rails for limiting the movement of said legs, upon the downward movement of said U shaped member.

GEORGE E. LOUCKS.
